**APPARATUS FOR THE MECHANICAL HANDLING
OF ELONGATE PRODUCTS OF A ROLLING
MILL**

William Udall, Sheffield, England, assignor of one-half to The Brightside Foundry & Engineering Co., Limited, Sheffield, England

Filed Jan. 4, 1961, Ser. No. 80,608

Claims priority, application Great Britain Jan. 5, 1960
6 Claims. (Cl. 198—29)

This invention relates to apparatus for the mechanical handling of elongate products of a rolling mill.

An object of the invention is to provide apparatus comprising a grid composed of a plurality of spaced apart side-by-side elements providing collectively a receiving surface for the step-by-step traverse therealong of elongate products in a direction transverse to the axes of said products, said grid including a rotatably driven aligning roller mounted for rise and fall movement into engagement with and disengagement from the elongate products for moving said products longitudinally at a stage in their step-by-step traverse along the grid and means for determining the extent of said longitudinal movement of said products.

A further object is to provide novel means for effecting rise and fall movement of the aligning roller by mounting said roller on the upper and free end of an oscillatable hollow arm pivotally mounted in a bearing, gearing accommodated in the pivotal end of said arm, said gearing driving a spindle extending through the oscillatable arm for carrying and rotating the aligning roller.

A still further object is to provide cam mechanism operable upon the arm externally thereof for effecting the oscillation thereof.

These and other objects will be apparent from the following description in which reference is made to the accompanying drawings.

In the drawings:

FIGURE 1 is a side elevation partly in section of a mechanical handling apparatus for delivering hot rolled bars from a rolling mill on to a cooling bed.

FIGURE 2 shows a part plan view of the apparatus of FIGURE 1.

Referring to the drawings, the apparatus comprises an inclined platform or grid A having a plurality of laterally spaced apart stationary elements 1, each of which is provided with a series of inclined surfaces, for example, three inclined surfaces 2, 3 and 4 which extend between an upper feed table B and a cooling bed C.

The lower end of the inclined surface 2 of an element is connected to the upper end of the inclined surface 3 of the same element by means of an upwardly directed step 8, and similarly the lower end of the inclined surface 3 of said element is connected to the upper end of the inclined surface 4 thereof by means of the upwardly directed step 9, these steps 8 and 9 constituting a first and a second station respectively on each element for receiving temporarily the hot rolled bars as they descend from the feed table B.

Lifting means for the hot rolled bars comprising two lifting plungers 10 and 11 are coupled by means of the connecting rods 12 and 13 to an oscillatable member 14 rotatably mounted on a shaft 15. The plungers 10 and 11 have upper faces 16 and 17 respectively which are inclined so that when a plunger is in its upper position the upper face forms a "run off" surface to allow a hot rolled bar to run off the plunger on to the upper end of the adjacent inclined surface.

The apparatus also includes an aligning means in the form of a rotatably driven roller 18 mounted at the upper end of an oscillatable arm 19 which is itself pivotally mounted at its lower end in a bearing 20 beneath

2

the elements 1. The arm 19 can firstly be pivoted upwardly to bring the driven roller 18 into engagement with the underside of a hot rolled bar located at the second station and then pivoted downwardly to disengage the roller 18 from said hot rolled bar. This pivoted movement is controlled by a cam action comprising a roller 21 mounted on a lug 22 on the lower centre portion of the arm 19 so as to ride on a cam 23 eccentrically mounted on a bearing 24. The driven roller 18 is rigidly mounted on a driving spindle 25 which extends longitudinally through the arm 19 and is driven from a shaft 26 by a bevel or other suitable gearing 27 associated with the pivoted mounting of the arm 19.

It is to be understood that the platform or grid can have a set of laterally spaced side-by-side elements 1 and that a plurality of pairs of lifting plungers and a plurality of oscillatable roller carrying arms are likewise provided for operation in some or all of the spaces between adjacent elements.

In the operation of the apparatus, hot rolled bars arrive in succession from the rolling mill on to the upper feed table B, these bars then being swept off said table so that they can run down the set of upper inclined surfaces 2 to arrive in succession at the first station. The lifting plungers 10 thus operate to lift the hot bars on to the upper end of the next set of inclined surfaces 3 so that these bars can run down to the second station where they are engaged by the rotatably driven roller 18 of the aligning means; the oscillatable arm 19 and roller 18 operating to move the hot bars axially along the second station so that the one ends of said bars abut a stop member 28 provided for the purpose on the grid A. The oscillatable arm 19 then pivots downwardly to disengage the roller 18 from the hot bars, whereupon the lifting plunger 11 rises to lift said bars on to the upper ends of the set of lowest inclined surfaces from which said bars run down on to the cooling bed C. The lifting plungers 10 and 11 are controlled by the oscillatable member 14 so that as the plunger 11 at the second station falls, the plunger 10 at the first station rises again for the above described operation to be repeated on successive hot rolled bars arriving down the set of inclined surfaces 2. In addition, the aligning means is controlled by the gearing 27 and cam 23 so that a hot rolled bar arriving at the second station is firstly moved axially into alignment by the roller 18 and then raised on to the upper end of the inclined surface 4 by the lifting plunger 11.

The stop member 28 is provided with a handle 29 and with two legs 30 for removable fitment into apertures 31 therefor at the second station of the inclined surfaces, these apertures being provided at intervals in said surfaces for receiving the stop member 28 as required according to the length of the hot rolled bars being dealt with.

What I claim is:

1. Apparatus for the mechanical handling of elongate products of a rolling mill comprising a grid composed of a plurality of spaced apart side-by-side elements providing collectively a receiving surface for the step-by-step traverse therealong of the elongate products in a direction transverse to the axes of said products, an oscillatable hollow arm pivotally mounted in a bearing below the grid and extending upwardly and inclinedly towards said grid, a spindle extending through said arm carrying and driving an aligning roller mounted thereon beyond the limits of the upper end of the oscillatable arm, driven gearing accommodated in the pivotal mounting of the oscillatable hollow arm for driving the spindle, and means for oscillating said arm.

2. Apparatus for the mechanical handling of elongate products of a rolling mill comprising a grid com-

posed of a plurality of spaced apart side-by-side elements providing collectively a receiving surface for the step-by-step traverse therealong of the elongate products in a direction transverse to the axes of said products, an oscillatable hollow arm pivotally mounted in a bearing below the grid and extending upwardly and inclinedly towards said grid, a spindle extending through said arm carrying and driving an aligning roller mounted thereon beyond the limits of the upper end of the oscillatable arm, driven gearing accommodated in the pivotal mounting of the oscillatable hollow arm for driving the spindle, and means for oscillating said arm, said means comprising cam mechanism operable upon the arm.

3. Apparatus as claimed in claim 2, characterized in that the oscillatable arm is provided with lug carrying a roller in riding engagement with the periphery of an eccentrically mounted cam.

4. Apparatus for the mechanical handling of elongate products comprising a base, a platform on said base having at least one element provided with a series of inclined surfaces extending between an upper feed table and a lower receiving table for the descent of said products at right angles to their length in sequence along said inclined surfaces to convey the products from the feed table to the receiving table, two upwardly directed steps each extending from the lower end of a preceding inclined surface of the series to the upper end of the adjacent succeeding inclined surface to form a first and a second station respectively for the temporary reception of products in their descent, lifting means at each station for raising a product from each one of said stations for descent therefrom along a succeeding inclined surface,

5 mechanism coupling said lifting means so that as the lifting means at one station is raised the lifting means at the other station is lowered, aligning means to effect longitudinal movement of a product at said second station, 10 stop means associated with said second station, and means for operating said aligning means when the lifting means at said second station is in its lowered position to move a product longitudinally at said second station against said stop means, said aligning means comprising an oscillatable arm pivotally mounted by one end on said base below said platform, a roller rotatably mounted on the free end of said arm, an aperture in said platform at said second station, means for oscillating said arm to cause said roller to project through said aperture, and means for driving said roller to move a product in contact therewith towards said stop means when said roller is projected through said aperture.

15 5. Apparatus according to claim 4 in which said oscillatable arm is hollow and said roller is driven by a driving spindle running through the hollow oscillatable arm.

6. Apparatus according to claim 6 in which said driving spindle is driven by right angle gearing concentric with the pivotal mounting of the oscillatable arm.
